DESIGN FOR A SODA GLASS OR ARTICLE OF SIMILAR NATURE

T. Clarence Heisey, Newark, Ohio, assignor to
A. H. Heisey & Company, Newark, Ohio, a corporation of Ohio

Application February 7, 1940, Serial No. 90,082

Term of patent 14 years

To all whom it may concern:

Be it known that I, T. Clarence Heisey, a citizen of the United States of America, residing at Newark, in the county of Licking and State of Ohio, have invented a new, original, and ornamental Design for a Soda Glass or Article of Similar Nature, of which the following is the specification, reference being had to the accompanying drawing, forming a part thereof.

Figure 1 is a perspective view of a soda glass,
showing my new design.

Figure 2 is a vertical sectional view.

I claim:

The ornamental design for a soda glass or article of similar nature, substantially as shown.

T. CLARENCE HEISEY.
